UNITED STATES PATENT OFFICE.

ENOCH WESTERDAHL, OF THIEF RIVER FALLS, MINNESOTA.

REVOLVING MULTIPLE-FUSE BLOCK.

No. 887,559.

Specification of Letters Patent.

Patented May 12, 1908.

Application filed May 27, 1907. Serial No. 375,935.

To all whom it may concern:

Be it known that I, ENOCH WESTERDAHL, a citizen of the United States, residing at Thief River Falls, in the county of Red Lake and State of Minnesota, have invented certain new and useful Improvements in Revolving Multiple-Fuse Blocks; and I do declare the following to be a full, clear, and exact description of the invention, such as will 10 enable others skilled in the art to which it appertains to make and use the same.

This invention relates to improvements in multiple fuse blocks, in which a plurality of fuses are carried, so that when one fuse burns out another may be quickly brought into position and the circuit at once restored.

The object of the invention is to provide a simple and efficient device of this class, which may be cheaply manufactured and quickly 20 and easily operated.

In the accompanying drawings—Figure 1 represents a perspective view of this device unloaded and with one fuse shown in dotted lines in the act of being inserted; Fig. 2 represents a longitudinal section thereof; and Fig. 3 represents a transverse section, taken on line 3—3 of Fig. 1.

In the embodiment illustrated, a supporting frame is shown consisting of a base plate 30 having screw holes as 2 for securing it to a wall or other structure, and provided with spaced blocks 3 and 4, between which the fuse-carrying element 10 is adapted to be rotatably mounted. The inner faces of these 35 blocks 3 and 4 have annular recesses of a proper depth to provide inwardly-extending, annular flanges 5 and 6, which form guards for the ends of the fuses carried by the member 10 to hold them against lateral displacement, and central bosses 5' and 6', between 40 which the fuse-carrying member 10 is mounted. The end walls of these annular recesses limit the longitudinal movement of the fuses and prevent their disengagement from the 45 block or member 10. A socket 7 is formed in the end wall of one of the annular recesses to provide for the insertion of one end of a fuse thereinto when the member 10 is being loaded.

The fuse-carrying member 10 is fixed to a shaft 8, preferably by means of a bolt or pin 9, which passes transversely through the member 10 and the shaft 8. This shaft 8 extends longitudinally through the blocks 3 and 4 and is rotatably mounted in bearings in 55 said blocks, and it projects at one end beyond

the outer face of one of the blocks and is provided with a knob 8' for turning it. This fuse-carrying member 10 is preferably made cylindrical and has a plurality of longitudinally-arranged grooves 11 formed in its periphery, said grooves being of a depth sufficient to hold the fuses 20 so that their sides will be approximately flush with the periphery of the cylinder 10. This cylinder 10 is of 60 slightly less length than the fuses, so that the ends of the fuses may extend beyond the opposite end of the block 10 into the recesses in the inner faces of the blocks 3 and 4. Projecting into the recesses in the inner faces 70 of said blocks 3 and 4 at opposite sides thereof are oppositely-disposed pairs of spaced, spring contact plates, as 12 and 13, between which the ends of the fuses are adapted to be inserted to establish the circuit. 75 These springs are made in the form shown in Fig. 2, and the shanks thereof extend longitudinally through the blocks 3 and 4, those in one block being in longitudinal alinement with those in the other block. 80 These plates 12 and 13 are arranged in pairs at opposite sides of the blocks 3 and 4, and the plates of each pair are connected at their outer ends by a contact screw as 17, which extends transversely through the sides of the 85 blocks 3 and 4 and through the plates and form binding posts for the wires.

The inner ends of the plates 13 are offset with their terminals extending parallel with the outer ends of the plates 12 and are adapted to fit in the recesses in the inner faces of the blocks. The offset portions 14 being of a length slightly less than the width of the fuse ends permit said fuse ends to be sprung between the parallel ends of the plates 12 and 13 and be held thereby in operative position. 90 These pairs of plates at opposite sides of each block are connected with the circuit wires 15 and 16. These wires extend through openings in the base plate 1 and in the blocks 3 and 4, and each is clamped between the head of the screw, as 17, and a brass washer or plate, as 18, at the respective ends of the blocks. The wires 15' and 16' are used when 95 it is desired to pass the circuit wires through the ends of the blocks 3 and 4 instead of through the base plate 1.

In the use of this device, the parts being assembled as shown in Fig. 1, the rotatable fuse-carrying member 10 has a fuse placed in 110 each of its longitudinal grooves by turning the block until one groove registers with the

socket in the end wall of the block, when one end of a fuse may be inserted therein and then moved longitudinally in the other direction until the opposite end passes under the flange of the other block. The member 10 is then turned sufficiently to cause the next groove to register with the socket, and so on, until all the grooves are filled. When so filled, two of the fuses at opposite sides of the frame are held between the ends of the spring contact plates in the blocks 3 and 4 until the shaft is turned to bring other fuses into the places of those desired to be removed.

I claim as my invention,—

- 15 1. A multiple fuse block comprising a base plate provided with spaced blocks, the inner faces of said blocks having annular recesses formed therein and the end wall of one of said recesses having a socket therein, and a fuse-carrying member revolvably mounted between said blocks and having longitudinal grooves therein adapted to register successively with said socket.
- 20 2. A multiple fuse block comprising a base plate provided with spaced blocks, the inner faces of said blocks having annular recesses formed therein, transversely-spaced spring contact plates projecting into said annular recesses, and a fuse-carrying member rotatably mounted between said blocks and having a plurality of fuse seats.
- 25 3. A multiple fuse block comprising a base

plate provided with spaced blocks, the inner faces of said blocks having annular recesses formed therein, oppositely-disposed pairs of transversely-spaced contacts arranged in said annular recesses, and a fuse-carrying member revolvably mounted between said blocks and having a plurality of fuse seats.

4. A multiple fuse block comprising a base plate provided with spaced blocks, the inner faces of said blocks having annular recesses formed therein, oppositely-disposed pairs of transversely-spaced contacts arranged in said annular recesses, the plates in one block being arranged opposite those in the other block and in longitudinal alinement, and a fuse-carrying element rotatably mounted between said blocks.

5. A multiple fuse block comprising a base plate provided with spaced blocks, the inner faces of each having annular recesses formed therein to provide annular flanges and central bosses on said faces, and a fuse-carrying member revolvably mounted between said bosses and having longitudinally-arranged fuse seats.

In testimony whereof I have hereunto set my hand in presence of two subscribing witnesses.

ENOCHE WESTERDAHL.
